CLAIM

The ornamental design for a stove door, as shown and described.

DESCRIPTION

FIG. 1 is a perspective view of a stove door showing our new design;

FIG. 2 is a front view thereof;

FIG. 3 is a right side view thereof;

FIG. 4 is a left side view thereof;

FIG. 5 is a top plan view thereof; and,

FIG. 6 is a bottom plan view thereof.

The broken lines shown in FIGS. 1 and 2 depict portions of the stove door that form no part of the claimed design.
